(57) **CLAIM**

We claim the ornamental design for a door for footwear care machine, as shown and described.

DESCRIPTION

FIG. 1 is a front perspective view of a door for footwear care machine showing a new design;

FIG. 2 is a rear perspective view thereof;

FIG. 3 is a front view thereof;

FIG. 4 is a rear view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a perspective view showing a state in use of the door combined with the main body; and,

FIG. 10 is a perspective view showing the door transitioned to an alternate transparent state, shown in a state of use combined with the main body.

The broken lines depict portions of the article and environment that form no part of the claimed design.
